UNITED STATES PATENT OFFICE.

EDWIN FIDELL, OF JERSEY CITY, NEW JERSEY.

MECHANISM FOR AFFIXING STAMPS AND SIMILAR DEVICES.

No. 878,514.

Specification of Letters Patent.

Patented Feb. 11, 1908.

Application filed June 16, 1905. Serial No. 265,488.

To all whom it may concern:

Be it known that I, EDWIN FIDELL, a citizen of the United States, and resident of Jersey City, in the county of Hudson and State of New Jersey, have invented certain new and useful Improvements in Mechanism for Affixing Stamps and Similar Devices, of which the following is a specification.

This invention relates to means for applying revenue stamps or similar devices to wrapped packets of merchandise, say tobacco, and as disclosed in the present case, involves novel mechanism admitting of the convenient feeding of sheets of revenue stamps, the latter being of extended narrow character and successively joined together along parallel transverse rows of perforations.

The construction and operation of this stamp feeding mechanism results in each stamp being accurately detached from its sheet and maintained so that it can be picked up by a stamp-carrying head. The stamp-carrying head is conditioned to successively convey the stamp to a device for applying paste to the stamp back and then to a position above a wrapped packet, after which, the head is operated to apply the pasted stamp to the packet, a stripper being combined with the head to insure the timely disengagement of the stamp from said head. Where the packet and stamp are such that portions extend beyond the packet, a supplemental device serves to properly press the stamp extensions in contact with the contiguous surfaces of the packet. As will be hereinafter manifest, the novel stamp feeding and applying mechanism can be utilized in situations other than those set forth in the present case.

There are other highly advantageous features connected with the invention which besides those alluded to, are clearly explained in the subsequent detailed description.

The improvements are illustrated in connection with an organized machine wherein a number of pairs of wrapping-jaws, their particular actuating devices, and the coacting stamping conveying and applying heads are arranged to partake of a circular traverse, thus permitting the jaws, coacting devices and the heads to perform their several functions, both rapidly and with high efficiency, and thereby permitting large quantities to be stamped in a continuous manner and in an exceedingly limited period of time.

In the accompanying drawings forming

part of this specification—Figure 1, is an elevational view of a considerable part of one form of a wrapping machine, and illustrating my novel stamp feeding and applying mechanism in connection therewith. Fig. 2, is an enlarged detail plan view of certain parts of the wrapping machine, and more particularly showing the stamp feeding and applying mechanism. Fig. 3, is an enlarged detail plan view of a pair of the complementary wrapping jaws together with the coacting mechanism more especially pertaining thereto. Fig. 4, is an elevational view partly in section, of the features represented in the preceding figure, certain actuating parts below the plane of the jaws, being more clearly illustrated and dotted lines indicating the manner in which the projected downward movement of the stamp-carrying head operating in connection with said jaws, is effected. Fig. 4^a, is a detail perspective view of the stationary cam disk mounted on the main or supporting standard. Fig. 5, is an enlarged detail elevational view of certain parts of the wrapping machine and disclosing more especially the stamp-feeding and applying mechanism viewed from a position to the left of Fig. 2. Fig. 6, is an enlarged detail sectional view of features at the inner portion of the stamp-feeding mechanism, and illustrating more particularly the manner in which a stamp is detached from its sheet by being broken along the line of its perforated connection. Fig. 7, is a somewhat similar view showing how the detached stamp is engaged by a stamp-carrying head. Fig. 8, is an enlarged detail sectional view, illustrating a stamp-carrying head in the act of applying a pasted stamp to a wrapped packet, a portion of a tappet being shown to indicate the manner of disengaging the stamp from the head. Fig. 9, is a somewhat similar view of the supplemental stamp-affixing device and indicates the manner in which the same operates to perform its function. Fig. 10, is a detail view of the stamp-feed frame and illustrating the removable character of the side bar for permitting the convenient application and removal of the endless feed-bands. Fig. 11 is an enlarged cross sectional view of the device for applying paste to the stamp back. Fig. 12 is a side view showing the mechanism for affixing the stamp to the packet.

Similar reference characters are employed to designate corresponding parts in the several views wherein they occur.

I have disclosed my improved stamp-feeding and affixing mechanism in connection with a machine for the application of wrappers to packets of tobacco, and which machine forms the subject matter of a separate application for patent filed by me, on December 2, '04, Serial No. 235,268, to which application reference may be had for a full understanding of the complete details and operation thereof. It is thought that it will suffice in the present case, to state that the supporting frame of the machine includes a main column or standard A, preferably presented by a single casting and of the configuration generally indicated in Fig. 1, said standard being hollow throughout its length and embodying a lower portion A', which downwardly enlarges and merges in a circular base plate A², resting on, and if necessary, bolted to the floor.

Within the standard and turning in suitable bearings provided by the same, is a vertical shaft B, the upper projecting portion of which has firmly secured thereto a bevel gear wheel b, the hub of which rests upon the upper bearing. Previous to lowering the shaft into position, a gear wheel b', is introduced through a hand-hole a⁴, in the lower portion A', and so held that the shaft in descending will pass through the opening in the wheel b', and the latter can then be properly fastened to said shaft.

Motion is communicated to the shaft through the medium of a bevel gear wheel b², meshing with the wheel b', and secured on the inner end of a lower horizontal shaft B', turning in bearings b³, b⁴, provided at the ends of an oval-shaped support B², of sectional character and bolted on the base plate A², the outer projecting portion of the shaft B', carrying the fixed and idle pulleys b⁵, b⁶, for coöperation with belt gearing transmitting power to the machine.

Revolutely supported on the standard is a vertical sleeve B³, having secured thereto a horizontal gear wheel B⁴, of comparatively large diameter. The sleeve B³, is designed to be rotated on the standard, through the medium of a gear-pinion b⁷, secured on the upper end of a vertical stub-shaft revolutely supported in a bearing b⁸, formed on the support B², the lower end of said stub-shaft having fastened thereto, a bevel wheel b⁹ meshing with a bevel gear pinion b¹⁰, on and revolving with the drive shaft B'.

The sleeve B³, supports and is adapted to rotate a bowl shaped carrier B⁵, conditioned as generally indicated and externally provided with horizontal flanges b¹¹, b¹², annularly disposed, the flange b¹¹, being intermediate located while the flange b¹², is at the upper edge of the carrier.

Bolted on the upper flange b¹², are the inner end portions c of radially extending flat horizontal arms C, arranged in a circular se-

ries, the said inner portions being of such segmental shape that they will fit edge to edge on the flange and thereby collectively conform to the circular character of the latter and provide for the radial disposition of the arms.

On each portion c, is the base of a bracket C', comprising short inner and outer vertical risers c', c², each of which has at its upper end a transverse tubular bearing c³, c⁴, revolvably in each of which is a pin c⁵, c⁶, having secured on one projecting end of each, a gear pinion c⁷, c⁸. The hub c⁹, of a sector-shaped member C², is revolvably confined on a horizontal stud laterally projecting at one side of a lower depending ear c¹⁰, of the bracket. The hub has integrally at its inner side a short tubular socket c¹¹, which is slightly obliquely disposed and which receives the inner end of a short journal carrying a revolvable roller c¹². A set screw c¹³, bearing in the socket, admits of the accurate clamping of the shaft in the socket. The upper curved rim c¹⁴, of the member C², is peripherally provided with rear and forward series of teeth c¹⁵, c¹⁶, with which the pinions c⁵, c⁶, mesh respectively. Also secured on the pins c⁵, c⁶, are upwardly extending short parallel arms c¹⁷, c¹⁸, the upper ends of which are pivotally connected to the lower ears of the bar C³, above and radially coinciding with the appropriate arm C, beneath. The downwardly curved forward end of the bar has a transverse horizontal head C⁴, in which bear a series of small vertical pins c¹⁹, portions of which project at the underside of the bar and are provided at their lower ends with tapering contractions c²⁰, merging in spherical extremities c²¹, as illustrated more clearly in Figs. 4, 6, 7, and 8.

Centrally at the upper side of the head C⁴, is an integral tubular boss c²², the interior of which intersects a contracted opening in the lower portion of the head. Vertically guided within said opening and extending up through and above the boss, is stem c²³, of a stripper C⁵, perforated for the vertical play therein of the headed portions of the pins c¹⁷. The upper portion of the stem terminates in an enlargement to form an abutment c²⁴, within the top part of the boss, and between which and the bottom of the boss-interior is interposed a spiral thrust spring c²⁵, normally tending to maintain the stripper elevated against the head, so that the lower ends of the pins will project below the under surface of the stripper.

At an intermediate point of the arm C, is a small vertical bearing c²⁶, in which is rigidly mounted the lower end of a bent stop c²⁷, the upper forward portion of which is laterally disposed. The extremity of said arm is recessed to form a socket for the inner end of a forwardly extending upwardly turned hook c²⁸, also designed to serve as a stop, which latter and the stop c²⁶ 130

act to limit the relative opening movements of the pair of folding jaws D^2 , D^3 , operating in connection with each arm.

It is to be understood and as will clearly appear by reference to my said co-pending application, that each arm C , has thereon at its outer end, a packet holder C^6 , complementary to which are a pair of normally opened folding jaws D^2 , D^3 , the bottoms of which occupy such horizontal plane that they will support an unfolded wrapper immediately above the said packet holder C^6 , suitable packet feed-means being provided, whereby when each packet-holder and its attendant opened jaws come into juxtaposition to said feed means, a packet supported above said holder and jaws, will be seized by gripping devices and drawn with the wrapper down within the holder, this operation resulting in the wrapper acquiring two fold extensions, one longer than the other. As the arm with its partially unwrapped packet moves further in its circular path of traverse, the gripping devices release and recede from said packet, the jaws through actuating means successively acting to fold first the longer wrapper extension and then the shorter wrapper extension in overlying relation upon the packet. As the arm C under consideration, approaches the stamp-feeding and affixing mechanism, the jaw which made the first and longer fold moves to an open position, the outer jaw still confining the shorter overlay fold. These several movements are effected by cams on the main frame of the machine, and cam shoulders at the underside of a disk F , stationary on the central standard A , the said shoulders serving in connection with a lever E , pivoted on the lower flange b^u , of the revolving carrier.

The stationary disk F , on the standard A , occupies a position in the upper part of the carrier B^5 , and has upper and lower annular ways f , f' , varying at certain determined points to present the requisite cams. By comparing the detail perspective view, Fig. 4^a, with the relative position of the standard A , Fig. 1, it will be noted that both positions correspond so that the particular location of the upper and lower cams with regard to the rest of the machine, will be generally understood. The upper way involves two recesses or depressions f^2 , f^4 , and an intermediate cam f^3 . The weight of the roller c^{10} , pertaining to the sector shaped member C^6 , together with the journal parts of said roller and the arm C^3 , and its connections, will suffice to maintain such roller in contact with the way f , and follow the depressions and cam therein.

It will be well to state at this point of the specification, that the construction previously described, in so far as it relates to the groups of elements represented by the radial arm C , bar C^3 , box C^6 , complementary wrap-

ping jaws D^2 , D^3 , lever E , and all the immediate appurtenances of said elements, are duplicated to any desired extent and number, and all radially disposed in a horizontal arrangement and conditioned to coöperate with other parts of the machine, whereby each group will, in regular and consecutive order undergo a corresponding series of operations.

Rigidly bolted to the top of the sleeve A^4 , 75 rotatably supported on the upper end of the standard A , is the inner integral circular flange i , of an extension arm I , which overhangs the body of the machine and terminates at its outer extremity in a short bend 80 having a disk flange i' . A short vertical hanger I' , has at its upper end a flange disk i^2 , corresponding with and bolted to the disk i' , and at its lower position but to one side said hanger rigidly carries a radially positioned bar I^2 , having a slight inclination in the direction of its outer end as indicated in Figs. 1, 5, 6 and 7. It will be noticed by reference to the last two mentioned figures, that the inner end of the bar I^2 , is configured to provide two upper bearings and a lower intermediate bearing, arranged in triangular relation, the bearing at the extreme inner end of the bar being in a slightly lower horizontal plane than the companion upper bearing. Revolvably mounted in these bearings are three shafts I^3 , I^4 , I^5 , of comparatively small diameter and which are maintained in braced relation through the medium of a side bar I^7 , in the latter of which 100 bear the upper shafts I^3 , I^5 , and a spindle I^x , on which the lower shaft, which is of tubular character turns. A bar I^6 , has a readily detachable engagement with the right hand end projecting portion of the shaft I^3 . The 105 outer ends of the bars I^2 , I^7 , have tubular bearings in which is revolvably supported a counter shaft I^8 , with the right hand end portion of which, Fig. 1, the outer end of the bar I^6 , is adapted to be detachably engaged. Secured on the shafts I^3 , I^5 , and spindle I^x , at 110 points between the bars I^2 , I^7 , are small pinions i^3 , Figs. 2, 5, 6 and 7, the pinion of the spindle I^x , simply serving to communicate motion to the pinion of the shaft I^5 , at 115 the end thereof. Projecting immediately outside of the bar I^7 , is a small sprocket wheel i^4 , which is geared by a chain belt i^5 , with a sprocket wheel i^6 , secured on the projecting left-hand end of the outer shaft I^8 . It may be well to here state, that the detachable engagement of the bar I^6 , is maintained through providing the end portions of said bar with deep vertical recesses rounded at 120 their tops and opening at the bottom edge of the bar whereby the latter can be manipulated to cause its parts forming the recesses, to fit snugly within the annular channels therefor, appropriately in the shafts I^3 , I^5 , 125 see Fig. 10. Consequently the said bar and 130

the said shafts will be locked in engagement. The principal object of this arrangement is to facilitate the application of endless bands or tapes i^7 , around the shafts I^3, I^8 , said bands being disposed in parallel relation. The functions of these bands will presently become apparent.

Referring to Figs. 6 and 7, firmly supported by the bars I^2, I^7 , immediately at the inner side of the position of the shaft I^3 , is a cross bar I^9 , which is recessed at one side to closely conform to the rounded surface of the adjacent part of the shaft I^3 , whereby the horizontal top edge of the bar will overhang and be flush with the top of said shaft. Secured to this bar I^9 , is a narrow transverse stamp-bed comprising a bar i^8 , longitudinally recessed for the reception and positive securement therein of a section i^9 , of yielding material which is exposed through an elongated opening in the top of the bar, and is flush with the same. The stamp-bed thus formed is so secured to the bar I^9 , that the horizontal upper surface will be slightly below the top of said bar thereby converting the upper edge portion of the latter into a transverse shoulder i^{10} . The three shafts I^3, I^4, I^5 , have extremely narrow bands i^{11} , passing around the same, and also over the bar I^9 , and the stamp-bed. The bands i^{11} , are spaced in parallel relation and for the purpose of so maintaining them. The shafts I^4, I^5 , can have annular surface channels i^{12} , for receiving and retaining said bands in proper guided position. A short arm i^{13} , adjustably clamped externally on the bar I^7 , extends above the same and carries a revoluble roller i^{14} , bearing on the upper pass of the gear chain i^5 , to take up slack therein. 40 This tightener appears in Fig. 5, but is omitted from Fig. 2.

An extended tubular bearing J , has a strong connection with the arm I , at one side of the latter adjacent to the forward curved end portion thereof, the bearing extending considerably above the arm and integrally presenting a short inner horizontal bracket j , provided at its extremity with a short vertical guide j' , which is shown as having flat parallel sides. Slidably in the bearing J , is a stem j^2 , which is of such length that end portions thereof are adapted to project above and below the bearing J . A small cross head J' , has a socket j^3 , secured in which is the upper end of the stem j^2 , whereby said head is supported horizontally in position, the rear bifurcated end j^4 , of the head slidably embracing the guide j' , which thereby permits the head to move vertically but contributes to prevent lateral play of the same. A strong spiral thrust-spring j^5 , embracing the upper part of the stem j^2 , is interposed between the bearing J , and socket j^3 , of the cross head J' , and normally tends to maintain said head and the stem in an elevated

position. Pivots on a stud projecting at the front of the socket j^3 , is the upper end j^5 , of a depending pitman j^6 , the lower end of which is pivotally attached to the outer end of an arm j^7 , secured on the outer end of a shaft J^2 , revolvably supported in an extended radial bearing j^8 , bolted on the side of the arm I , opposite to that at which the bearing J , is situated. As indicated in Figs. 2 and 5, the inner projecting end of the shaft J^2 , has rigidly affixed thereto a crank j^9 , which extends horizontally toward the left and carries a spring mounted roller j^{10} , in operative relation with a cam j^{11} , on a shaft J^3 , counter to the shaft J^2 , said cam arrangement being designed to positively rock the latter shaft as the counter shaft is revolved. It will be seen that the lifting of the crank j^9 , by the cam j^{11} , will swing the arm j^7 , downward, and said arm through the pitman connection, depress the head J' , and the stem j^2 , counter to the action of the spring j^5 . When the cam j^{11} , turns to permit the lowering movement of the crank j^9 , the spring j^5 , will obviously operate to restore the head J' , and stem to their elevated position. A further effect of the spring is to maintain the crank-roller j^{10} , in contact with the cam j^{11} .

The shaft J^3 , which is of the extended length illustrated most clearly in Fig. 2, is revolvably supported in a rear horizontal bracket bearing j^{12} , rigidly projecting from the side of the arm I , said shaft being revolvably supported at its outer portion by one of a pair of forwardly disposed horizontal bearings j^{13}, j^{14} , presented by a member J^4 , rigidly connected to the outer bent part of the arm I . On the shaft J^3 , immediately in front of its bearing j^{13} , is secured a gear wheel J^5 , adapted to be driven by a similar wheel J^6 , meshing therewith and secured on the forward portion of an extended shaft J^7 , supported in the bearing j^{14} , and also in a bearing j^{15} , the latter rigidly on the side of the rear part of the arm I , contiguous to its connection with sleeve A^4 , at the top of the standard. On the inner extremity of the shaft J^7 , is bolted a bevel gear wheel j^8 , which meshes with the wheel b , on the upper part of the shaft B , and thus provides for driving the shaft J^7 .

An arm J^8 , loosely supported on the forward extremity of the shaft J^7 , extends transversely as illustrated in Figs. 1, and 2, and has a curved end portion j^{17} , carrying a wrist-pin with which is pivotally connected the upper end of a vertical pitman j^{18} , the lower end of which is pivotally secured to the rear end of a short rocker-arm j^{19} , loosely mounted at its front end on a stub-shaft J^9 , rigidly secured to the bars I^2, I^7 . A gear wheel j^2 , is also loosely confined on the shaft J^9 , and has revolvble therewith, a ratchet wheel j^{20} , with the teeth of which engages a

gravity pawl j^{20} , carried by the rocker-arm. The gear wheel j^{20} , meshes with the pinion j^x , secured on the outer shaft I^8 . Revolubly mounted on the rear of the curved end portion of the arm J^8 , is a roller j^{23} , resting on a cam j^{24} , on the forward end of the shaft J^3 , and revolubly therewith. The cam j^{24} , is somewhat elongated to adapt it as it rotates to impart a considerable lifting movement to the arm J^8 , and pitman and rocker arm actuated thereby, and hence as the shaft J^3 , is rotated by motion acquired through the gear wheels J^5 , J^6 , the rocker arm j^{19} , will be rocked by the alternate action of the cam and the gravity of the pivoted parts connected to said rocker arm, so that the pawl carried by the latter will intermittently rotate the ratchet wheel j^{21} , and correspondingly the gear wheel j^2 , pinion j^x , and shaft I^8 . Provision is thus made for effecting the intermittent rearward travel of the upper passes of the endless bands j^7 . The movement thus imparted to the bands is transmitted to the shaft I^8 , which through its gearing with the shafts I^4 , I^5 , causes a similar movement of the latter.

It will be understood that the ratchet wheel and its pawl and the actuating means for the latter are so proportioned that a sheet of parallel stamps successively joined together by perforated connections, resting upon the bands, will upon each positive movement of the ratchet wheel, be moved in the direction of the stamp bed to an extent somewhat greater than that required to feed one stamp, and when the feed has progressed sufficiently far, the stamp at the inner end of the sheet will overhang the bed, with the perforated connection of said stamp coinciding with the shoulder i^{10} , of the bar i^9 , this latter result being attained by fingers which project above the inner side of the stamp-bed during the stamp-feeding movement and serve as a gage for limiting the stamp above the bed.

Oscillatively supported to the lower rear part of a plate j^y , at the end of the stamp-bed and likewise in a second bearing (not shown) in the same horizontal plane, at the other end 50 of said bed, is a rod J^{10} , which carries a series of upwardly extending wire fingers j^{25} , which project up between the upper passes of the narrow bands i^{11} , for a short distance and are slightly curved so that when the rod J^{10} is in the position illustrated in Fig. 6, said fingers will bear against the adjacent upper corner of the stamp bed and thereby serve as the gage for each stamp as it is fed to a position above the bed as previously described.

60 A torsional spring j^{26} , on the end of the rod J^{10} , and secured to the latter and engaged with the adjacent plate j^y , tends to normally maintain said rod so that the fingers will bear against the stamp-bed. A curved tongue j^{27} , of wire is rigidly connected at one

end to the projecting part of rod J^{10} , and extends within the machine so as to be struck and depressed by the bars C^3 , as the latter approach the vicinity of the stamp-bed and assume a depressed position. Obviously, 70 the depression of the tongue j^{27} , will effect such partial turning of the rod J^{10} , that the fingers j^{25} , will be swung and held away from the bed. Upon the tongue being relieved of pressure, the torsional spring j^{26} , will operate 75 to restore the fingers to their former position.

The stem j^y , carries at its lower end a frame K , which is of the character and shape generally indicated in Fig. 1, and embodies a lower presser bar K' , which coincides vertically with the roller I^3 , and bar I^9 , contiguous to the stamp-bed. The presser bar comprises an extended rigid forward section k , clamped between which and an inner strip k' , is an extended section k^2 , of yielding material, the lower edge of the strip k' , being somewhat in a higher plane than the corresponding edge of the section k , whereby a lower horizontal rear lip k^3 , of the section k^2 , takes closely beneath the section k' . The 90 lower part of the section k^2 , is of such character that it normally expands below the plane of the lower edge of the section k , but when subjected to the pressure as it will be when the presser bar in its lower position, 95 said lip part will be compressed so that the entire under surface of the presser-bar will approximately conform to the surface upon which it is pressed.

The presser-bar is reinforced on its upper 100 side by a horizontally extended flat strip k^4 , upon which in turn is imposed another flat strip k^5 , of extended length, both of said strips being positively retained in position. The strip k^5 , constitutes the lower stationary 105 track of a horizontally elongated guideway within the frame K , the upper parallel track of said way being presented by a similar extended flat strip k^6 , yieldingly supported within the upper part of the frame opening, 110 by bolts k^7 , vertically movable in the frame-top and having embracing springs k^8 , interposed between said top and the strip k^6 .

A journal K^2 , has intermediately, a revoluble cylindrical barrel k^9 , confined by annular flanges k^{10} , in rolling contact between the tracks k^5 , k^6 , and on the inner projecting part of the journal, is a disk K^3 , of comparatively large diameter and revoluble with the barrel. This disk is preferably provided 115 peripherally with a flat tire k^{11} , of yielding material, rubber will satisfactorily answer on account of its frictional properties. This wheel occupies such position that when the frame K , is lowered said wheel will bear upon 120 the stamp-bed.

A pitman K^4 , has one end rigidly connected to the forward projecting portion of the journal K^2 , while to the other end of said pitman is pivotally attached, the lower 130

extremity of an inclined arm K^5 , of the peculiar configuration indicated in Figs. 2 and 5, wherein it is shown as having an upper yoke shaped portion k^{12} , straddling the upper part of a large disk-cam k^{13} , the latter secured on and revolving with the shaft J^3 . The short terminal leg k^{14} , of the yoke rigidly carries a rear horizontal pin k^{15} , oscillatively supported in a bearing integrally presented by a bracket K^6 , laterally projecting from the extended tubular bearing j^8 . A strong spiral spring k^{16} , torsionally tends to swing the arm K , to the right. Intermediately on the last mentioned arm, at the rear side thereof, is a roller k^{17} , which is maintained in peripheral contact with the disk-cam k^{13} , through the tension exerted by the torsional spring.

To the rail G' , below the stamp feeding and detaching mechanism, is the lower end of a standard L , the upper portion of which is bent to occupy a position some distance to the left of the feeding frame of which the bars I^2 , I^6 , I^7 , form parts. At the end of the standard, is an outwardly projecting pin to which is attached one extremity of a strong contractile spring l , which is shown in Figs. 1 and 2, and omitted from Fig. 5, for the purpose of clearly illustrating other parts, the opposite end of said spring being engaged with a hook l' , on the bearing j^{13} . This spring tends to normally maintain the stamp-feeding and detaching mechanism in the position illustrated in Fig. 2, said mechanism by reason of its swivel-support provided by the connection of the arm I , with the revolute sleeve A^4 , on the standard A , being capable of a limited movement in a direction counter to the tension of the spring l . The counter movement of the feeding and detaching mechanism referred to, is effected by means of a cam l^5 , on and rotating with the shaft J^3 , said cam bearing against a roller l^6 , revolutely mounted on a stud on the rear of the forked portion l^7 , of a horizontal arm L^2 , pivotally mounted at its outer end on the pin at the upper end of the standard L . The fork recess receives the shaft J^3 , and this arrangement not only provides for supporting the arm L^2 , at its inner end but permits the shaft J^3 , to move to the right with the feeding and detaching mechanism generally, without interruption of the supporting relation between the arm L^2 , and said shaft. Such movement to the right is obviously accomplished by the cam l^5 , pushing against the abutment presented by the roller l^6 , which results in forcing the feeding and detaching mechanism in the direction stated. For the purpose of aiding to support the weight of said feeding and detaching mechanism and contribute to guide the same during its shifting movements, an extended vertical stay L' , Figs. 1 and 5, has its lower end pivotally mounted in a chair l' , secured to the

floor, while the upper end of said stay has a thill connection with the bar I^2 , of the feed frame. The stay L' , is shown as comprising two sections having their threaded portions connected by a coupling l^4 , which arrangement facilitates the securement of the stay in position.

Referring to Figs. 2 5 and 11, N designates a rectangular paste-box or reservoir open at its top and supported within the machine considerably to the left of the vertical plane occupied by the arm I . This box is mounted upon the free inner end of a horizontal bar n' , the box being clamped to said bar by a spring yoke n , the horizontal part of which is secured to the bar while the vertical members of the yoke clasp the box on opposite sides. At one side of and contiguous to the stamp-bed, the box has a short vertical socket n^2 , for receiving the journal of a horizontally disposed roller N^2 . A grooved roller n^3 , occupies such position in the box that the upper portion of the roller n^3 , will be in a plane above the top edges of the box. This roller n^3 , is closely adjacent to the periphery of the roller N^2 , at the inner side thereof, the roller n^3 , being revolvably supported on a small journal n^4 , which latter is slidably mounted at its outer end in the short vertically slotted post n^5 , secured to the base of the box, an expanding spring being interposed between an abutment on the post and the lower side of the journal to yieldingly maintain the latter together with its roller in an elevated position.

At its outer end, the bar n^1 , has an upwardly extending leg n^6 , the upper end portion of which is bent horizontally inward to form a foot, which, together with the lower member of the bar, embraces a vertical pintle n^7 , carried by a saddle n^8 , the vertical turned ends of which are pivotally mounted on a horizontal rod n^9 , bolted to the end of an angle bracket N^3 , secured to a fixed part of the machine. This arrangement provides for a horizontal as well as vertical pivotal movement of the box. A bar N^4 , rigidly connected to one end of the saddle, extends below the feed frame and through a vertically extended loop n^{10} , at the upper end of a standard N^5 , bolted on the rail G' . The bar N^4 , is bent to present two downwardly converging portions. Manifestly, the nearer its point of convergence the bar N^4 , engages with the top part of the loop, the more central will be the saddle over the rod n^9 , and hence the higher will be the supported position of the paste box. By shifting the bar N^4 , so that the outer higher inclined edge thereof will be engaged with the loop top, the saddle will be tilted to depress and support the said box in an inoperative position. A set-screw n^{11} , in the top of the loop, is designed to engage within a notch in the end of the bar N^4 , and thus positively lock the

parts so that the paste box will be securely maintained out of position.

For the present, it need only be stated that the successive stamp-carrying heads C¹, pass over the box N at such altitude that a long narrow stamp at the lower side of each head will be lengthwise moved in contact with the parallel flanges of the roller n³, whereby, as the lower portion of said roller revolves in paste contained in the box, said flanges will apply the paste to the stamp-back at portions of the latter on both sides of the row of puncturing pins c¹⁷, which are engaged with the stamp. The accuracy of relation of the successive carrying heads with respect to the grooved paste roller, will be insured through the contact of the outer sides of said heads with the periphery of the horizontal roller N², which on account of the pivotal support of the box N, insures the paste roller nicely accommodating itself to the changes in the angular positions of the heads as they move in a circular orbit above the paste box.

An extended lever O, embodies adjacent to the left hand side of the arm I, Figs. 2, 5 and 11, a depending leg o¹⁴ which integrally carries a hub o, between and pivotally mounted in bearings o', o', on the side of the arm I, the inner end portion o², of said lever being arched to extend over to the opposite side of the arm I, where said portion carries at its extremity, a roller o³, resting on a cam O', secured to and revolving with the shaft J⁷. At its outer end the lever O, has bolted thereto cylindrical block O², at opposite sides of which are trunnions o¹, from which is pivotally suspended a horizontal bar o⁵, through the medium of ears o⁶, at the upper side of said head and revolvably engaging the trunnion end. Rigidly depending from the bar o⁵, at the central portion thereof, is a short hanger o⁷, in the lower bifurcated part of which is pivotally connected the forward end o⁸, of an extended rod O⁸, while the inner end of said rod is normally held spring retracted within a socket o⁹, secured to the arm I. The rod O⁸, carries somewhat adjacent to the socket a short laterally projecting journal o¹⁰, on which is revolvably confined a small roller o¹¹, which is adapted to be peripherally acted upon by a cam O¹, secured to and revolving with the shaft J³, at the inner end of the latter.

In one end of the bar o⁵, is bolted an extended depending shank p, which carries at its lower end a disk-shaped horizontal tappet P. A similar shank r, is secured in the other end of the bar o⁵, and carries at its lower end the supplemental stamp-applying device comprising an inverted horizontal yoke Q, a movable block Q', being supported vertically yielding in said yoke by means of bolts q, which are guided in bosses on the yoke top, and having expanding springs q², embracing said bolts and interposed between the block

and the yoke-top. Threaded bolts q³, tapped through the yoke top, provide for limiting the upward movement of the block within the yoke. Pivotaly mounted in vertical slots in the legs of the yoke, are small pressers q⁴, which are each enlarged at one end to present a projecting portion q⁵, disposed at an angle to the shank of its presser. These pressers are normally maintained in the position indicated in Fig. 5, by small contractile springs q⁶, which are attached to said pressers and to projections at the upper corners of the yoke. Small rollers q⁷, revolvably supported in end recesses therefor in the block, serve as anti-friction means for guiding the block in its movements in the yoke and also a suitable surface against which the upper ends of the presser shanks are held by the springs q⁶.

An extended horizontal rod O⁵, rigidly projects from the arm I, and has its outer end o¹², bent at an angle above the connection of the lever O, with the block O², so that a contractile spring o¹³, attached both to the end o¹², and to the block O², will serve to normally maintain the outer end of the lever elevated, and hold the inner end of the said lever in contact with the cam O'.

The machine will be constantly driven so that the bowl-shaped barrier B⁵, and parts supported thereby, will partake of a continuous horizontal circular movement to the right. Beginning with a pair of jaws D² D³, and their related features, as said jaws approach the vicinity of the packet feed means, said jaws will be in their mutually separated relation and with their allied features in the positions illustrated in Figs. 3 and 4. While the parts are so conditioned and moving as described, an attendant places an unfolded wrapper W, so that it is centrally supported immediately above the holder C⁶, the end portions of the wrapper snugly occupying the spaces within the jaws and supported on the jaw-bottoms. It will be noted that the transverse dimension of the bottom of the outer jaw D², or in other words, the distance from the outer wall of said jaw and the inner edge of the bottom of the same, is greater than the distance from the somewhat similar wall and edge of the jaw D³. A packet X, being placed in an elevated position by the packet feed means, the pair of jaws with accompanying holder C⁶, and grippers pass beneath said packet whereupon the gripping and lowering of the packet together with its wrapper within the holder occurs, and subsequent folding of the wrapper extensions takes place during the further traverse of said holder and immediate parts.

The holder C⁶, containing its infolded packet held as last described, now approaches the vicinity of the stamp-bed. Previously however, a stamp has been fed above the bed, and the head K, depressed so that its presser bar will clamp the feet immedi-

ately outside of the shoulder i^{11} , with which latter coincides the perforated connection of the stamp over the bed. The detaching disk K^3 , is caused to roll to the right along the bed, so that the stamp upon the same is detached from the rest of the stamp-sheet by being broken along the line of its perforated connection. The advantage of breaking the stamp as stated, in lieu of detaching it by cutting is that slight irregularities in the feed of the stamp-sheet, will in the aggregate, ultimately result in such variation from the correct severing position, that the stamps will become injured and serious loss be entailed. The pressing down of the head K , as previously mentioned will result in the spring k^8 , of the bolts k^7 , co-operating with the lower yielding section k^2 , to cushion said frame, the springs k^8 , being so compressed that the roller barrel k^9 , will bear with considerable friction at the underside of the track k^6 . When the disk K^3 , has reached the limit of its travel to the right and completed the stamp-detaching operation, the head K , then rises, leaving the detached stamp upon the bed. The rising of the head K , will obviously relieve the barrel k^9 , from the more pronounced frictional pressure of the track k^6 , so that the roller can then be retracted to its former position within the head without encountering any pronounced frictional retardation. As the head K , rises, the cam l^5 , operates to shift to the right the stamp feeding and detaching mechanism, so that the stamp bed correspondingly moves.

The approach of the holder C^6 , previously referred to as containing the infolded packet with the inner jaw D^3 , positively retaining one wrapper extension over the other, correspondingly brings the bar C^3 , above, in the vicinity of the stamp-bed. At this time, the roller c^{10} , pertaining to said bar, is entering the cam-depression f^2 , which has the effect of moving the sector member C^2 , to the position indicated in dotted lines Fig. 4, so that the pinions and arms c^{15} , c^{16} , of said bar will be moved outwardly and downwardly, and contacting in its downward movement with and depressing the tongue j^7 , of the small rod J^{10} , turning the latter to throw its fingers away from the bed. The further downward lateral movement of the bar C^3 , will result in the spherical ends of its pins c^{17} , puncturing the stamp upon the bed, said puncturing being facilitated by the yielding material forming part of the stamp-bed, and which material can be readily replaced when worn. The passage of the spherical heads through the stamp will cause the paper contiguous to said punctures to contract sufficiently to engage behind the heads and within the contracted parts of the pins, thereby insuring a positive engagement of the latter with the stamp. The roller c^{10} , immediately there-

after, rolls upon the cam f^3 , which obviously has the effect of securing a rising movement of the arm C^4 , picking up the detached stamp with its back or rear surface exposed. As the stamp-head in rising coincidentally partakes of a lateral movement to the left, the spring l , is now permitted to bodily retract the stamp feeding and detaching mechanism, including the stamp bed, so that the latter moves to a limited extent in the same lateral direction as the stamp bed, but sufficient however, to prevent the ends of the pins from exerting a dragging action at the stamp bed, which action might have the effect of tearing or mutilating the stamp. Said head C^4 , with its engaged stamp now moves over the paste box and the stamp receives parallel lines of paste along its back as previously described.

The roller c^{10} , next enters the cam depression f^4 , the effect being that after the head C^4 , has passed well to the left of the paste box, the head will be again lowered so that its stamp will bear lengthwise on the enwrapped packet in the holder beneath.

The cam O' , on the shaft J^7 , now raises the inner end of the lever O , so that the outer end of said lever is depressed whereby the tappet P , depresses the stem c^{22} , so that at the beginning of the subsequent movement of the bar C^3 , the stripper C^5 , will operate to strip the stamp from the lower ends of the pins c^{17} , said stamp by reason of its pasted back remaining adhering to the wrapped packet. The character of the punctures made by the spherical pin-ends, in the stamp, is such that when said ends are withdrawn from the stamp, the momentary pressing of the latter by the stripper face, will cause the minor displaced parts of the stamp to evenly fill the punctures, and thereby avoid any unsightly mutilation in the stamp. The cam O' , now permits the outer end of the lever O , to be lifted under the action of t^1 , spiral spring o^{13} , and coincidentally, the cam O^4 , operates to tilt the bar o^5 , so that the tappet and the supplemental stamp-affixing device will be swung outward from the path of the advancing bar C^3 . At this time, the grippers will be thrown away from the ends of the packet, which it will be understood have overhanging stamp extensions. The packet with the stamp partially pasted thereto, has now arrived at a position immediately below the supplemental affixing device, and the outer end of the bar C^3 , has risen to such plane, as will permit the spring retraction of the rod O^3 , the positive action of the cam O^4 , having terminated by this time. The spring retraction referred to, will cause the supplemental device to be swung inward immediately above the stamp-carrying packet, whereupon the cam O' , again operates to depress the outer end of the lever O' , so that the supplemental device is

forced down to cause its block Q', to bear upon the upper stamped surface of the packet and the block in vertically yielding will result in the stamp extensions being folded 5 downward and the pressers q⁴, being swung on their pivots so that their inner projections q⁵, will positively press said folded extensions against the end of the packet. The cam O', again ceases to act positively on the lever O, 10 permitting it to again rise, while the cam O⁴, again acts to tilt the bar o⁵, so that the supplemental device can be swung out of the way of the succeeding advancing bar C³. It will be understood that while the supplemental 15 device is securing the stamp ends of one package, the tappet P, is operating to strip the stamp from the head of a succeeding bar C³, and apply the same to its particular packet this relation of the supplemental 20 device and tappet being continued with regard to all the packets as they successively arrive at this part of the machine.

As the supplemental device rises and swings outward as shortly before stated, the stamped 25 packet continues in its path of circular movement to a point where it can be removed or discharged from the machine. Of course, before the supplemental device acts on the packet, the inner jaw D³, is withdrawn from 30 position with respect to its packet.

Having now described my invention, what I claim as new and desire to secure by Letters Patent is:

1. In mechanism of the character described, the combination with means for moving a packet in a horizontal curved path of travel, of means for feeding a sheet of joined stamps and for intermittently breaking a stamp therefrom, said feeding and 35 breaking means being laterally disposed and in a plane radial to the packet travel, means for applying paste to the stamp back, and means for affixing the pasted stamp to the packet.

2. In means of the character described, the combination with devices for the advancement of packets, of means for feeding and breaking a stamp from a sheet, a head movable with the said devices for engaging the 40 stamp, means for applying paste to the stamp back, and means for affixing the pasted stamp to the packet.

3. In means of the character described, the combination with devices for the advancement of packets, of means for feeding and breaking a stamp from a sheet, a head movable with the said devices for engaging a detached stamp, means for applying the paste 45 to the stamp back, and means for affixing the pasted stamp to the packet.

4. In means of the character described, the combination with devices for the advancement of packets, of means for feeding and breaking a stamp from a sheet, a head movable with the said devices for engaging the 50

detached stamp, means for applying paste to the stamp back, means for affixing the pasted stamp to the packet, and means for removing and delivering the stamped packet.

5. In means of the character described, the combination with devices for the advancement of packets, of a head movable with the said devices and adapted to engage the stamp, means for breaking the stamp from a sheet, means for applying paste to the stamp back, and a stripper carried by the head and adapted to disengage the stamp and affix it to the packet.

6. In mechanism of the character described, the combination with means for moving a packet in a horizontal curved path of travel, of means for feeding a sheet of joined stamps and for intermittently breaking a stamp therefrom, said feeding and breaking means being laterally disposed and in a plane radial to the packet travel, means for applying paste to the stamp back, means for affixing the pasted stamp to the packet, the ends of the stamp being of extended length relative to the packet, and supplemental devices for affixing the overhanging ends of the stamp.

7. In means of the character described, the combination with a stamp bed and mechanism in relation thereto for feeding a stamp sheet, of a vertically movable frame for clamping the stamp sheet contiguous to said bed, a stamp detaching disk carried by said frame and adapted to roll along the stamp bed to detach a stamp, means for moving 50 packets in relation to said bed, stamp affixing means, movable coincident with said packet moving means and adapted for engaging the detached stamp for affixing it to a packet, and a paste applying device in contact with 55 which the stamp affixing means moves the stamp before applying the same.

8. In means of the character described, the combination with a stamp bed, and devices for moving packets in relation to said bed, of means for shifting the latter, stamp affixing means coincidently movable with said bed and adapted to affix the stamp to a packet, and a paste device in contact with which the stamp affixing device moves the stamp previous to affixing the latter.

9. In means of the character described, the combination with devices for the advancement of packets, of a paste device, stamp carrying means adapted to move the stamp in contact with said paste device and subsequently affix the stamp to the packet, and a supplemental device including a spring yielding block and pivoted pressers, the latter adapted when the block bears on the packet, to swing inward and affix the overhanging stamp ends to the packet.

10. In means of the character described, the combination with devices for the advancement of packets, of stamp feeding and

detaching mechanism including a stamp bed and adjacent sheet supporting portion, a vertically movable frame having a lower yielding presser bar for clamping the sheet adjacent to said bed, a device for breaking the unclamped stamp from the sheet, and stamp engaging and paste applying means, said engaging means adapted to affix the pasted stamp to the packet.

10 11. In means of the character described, the combination with a stamp bed and stamp-feeding mechanism in relation thereto, of a

vertically movable frame for clamping the stamp contiguous to said bed, and a disk carried by the frame and adapted to roll along said stamp bed to detach the stamp from the sheet.

Signed at New York in the county of New York and State of New York, this 5th day of June A. D. 1905.
